MACHINE FOR PACKAGING PIPE CLEANERS
AND THE LIKE

Charles T. Gould, Walpole, Mass., assignor to
Philip S. Cushing, Norwood, Mass., and Jerome
Chaims, New York, N. Y., doing business as
American Pipe Cleaner Co., Norwood, Mass., a
co-partnership

Application October 22, 1946, Serial No. 704,901

6 Claims. (Cl. 226—2)

1

The object of this invention is to provide an efficient automatic machine for rapidly and accurately placing pipe cleaners or other slender elongated articles in containers. The pipe cleaners here referred to are of the familiar type consisting of two wires twisted together, between which tufts of fibers are confined and securely held. The containers in which the cleaners are placed may be envelopes made of paper or cardboard having substantial stiffness but flexible enough to be bowed from a flat condition by application of a moderate degree of force. Such envelopes may be open at both ends, or at one end only and closed at the other end and, in any case, their front and rear walls are connected together at the side edges.

A further object is to trim groups of pipe cleaners when they have been placed in the envelopes so that all members of the group will be of the same length and corresponding ends of all will be in the same plane.

A further object is to provide means for carrying the packages away from the loading point to a depository where they may be placed in cases for shipment.

The salient features of the invention in its preferred form comprise a magazine in which empty envelopes or equivalent containers are stacked, a feeder for removing the envelopes, one by one, from the bottom of the stack, means, of which the feeder may be a part, for spreading out the sides of the envelope after removal from the stack so as to open the receiving mouth of the envelope sufficiently to permit easy entrance of a bunch of pipe cleaners, means for advancing simultaneously a bunched number of pipe cleaner strips of indeterminate length into the open mouth of an envelope placed to receive them, means for cutting off the cleaner strips near the receiving mouth of the envelope after they have been advanced to a prescribed distance into the envelope, means for displacing the envelope with its contents of pipe cleaners from the filling position and at the same time pressing the sides of the envelope together and more or less flattening out the bunch of contained pipe cleaners, and a conveyer to which the packages of cleaners are delivered by the last named means and by which they are carried to a final depository.

Although the foregoing statement sets forth all of the principal parts of the hereinafter described embodiment of the invention, it is to be understood that the invention is not limited to the combination of all of such parts, but includes various partial combinations or subcombinations and modifications operative to place pipe cleaners and similar articles in envelopes or similar containers.

2

It is to be understood further that the term "pipe cleaner" as used in this specification is a descriptive term designating the material operated on by reference to the characteristics of articles commonly known by that term and is not a limitation of the invention to use in connection with goods which have the characteristics before described. In its broader aspects the invention is applicable to packaging slender elongated articles of other descriptions which are capable of being placed in envelopes or analogous holders for storage and shipment.

In the accompanying drawings I have shown a machine which embodies the principles of this invention in their presently preferred forms, and therein—

Fig. 1 is a side elevation of the machine;

Fig. 2 is a rear elevation, as seen from the right hand side of Fig. 1;

Figs. 3, 4, 5 and 6 are fragmentary sectional views taken on lines 3—3, 4—4, 5—5 and 6—6, respectively, of Fig. 2;

Fig. 7 is a plan view of the machine;

Fig. 8 is a sectional view on line 8—8 of Fig. 7; and

Fig. 9 is a fragmentary elevation of so much of the machine as appears in the upper right hand part of Fig. 2 as seen from in front of the machine.

Like reference characters designate the same parts wherever they occur in all the figures.

The frame of the machine supports a table 10 and contains bearings in which horizontal shafts 11, 12, 13 and 14 are contained. Shaft 11 is the main shaft and is driven by a belt 15 and pulley 16 from a motor or other source of power, not here shown. Shaft 12 is a cam shaft and supports a face cam 17 and disk cams 18, 19, 20 and 21. It is driven from shaft 11 by a train of gears 22, 23, 24 and 25 of which the first and last are secured to the shafts 11 and 12, respectively, and the intermediate gears 23 and 24 are connected together and mounted on a stud shaft 26.

Shafts 13 and 14 carry rolls 27 and 28, respectively, which are in surface contact with one another. The shafts 13 and 14 are coupled together by gears 29 and 30 at one end at a considerable distance from the rolls, and the end of shaft 14 nearest to roll 28 and opposite to the end on which gear 30 is secured is contained in a bearing box 31 which occupies a vertical guideway in the framework and is capable of rising and descending. This permits the upper roll 28 to press by gravity on the lower roll 27 and on

anything which may be located between the rolls; and also permits it to rise when a filled package passes through.

A pusher slide 32 is mounted in a guideway 33 in the top of the table 10 which extends in alignment with the nip of the rolls 27 and 28 in a direction perpendicular to the common plane of the roll axes. A magazine 34 is erected on the table over the slide 32 and has interior dimensions constituted and disposed to contain a pile of pipe cleaner envelopes *a* with their side edges parallel to the rolls. Such envelopes are commonly made of stiff paper or cardboard with a length of 7 inches, more or less, and a width of 3 inches, more or less, and are open at both ends and closed at both side edges. Or they may be closed at one end.

This magazine is set back from the rolls a sufficient distance to permit emergence of an envelope from its bottom far enough to provide a space in which the later described suction devices can act on the envelope after its advancing side edge has encountered the nip of the rolls. Preferably the distance between the nip of the rolls and the nearer boundary of the magazine is approximately equal to the width of envelopes of the size which the magazine is adapted to contain, although it may be greater or slightly less.

The guideway 33 extends from the edge of the table nearest the rolls a distance great enough to permit backward movement of the pusher 32 until its forward end is clear of the magazine, and advancing movement of the pusher far enough to bring an envelope against the nip of the rolls and a slight distance further. This guideway and the pusher are preferably as wide as the length of the envelopes, or approximately so.

The pusher is moved back and forth by a lever 35 which is pivoted at its lower end to a bracket 37 on the frame and the upper of which enters a slot in the pusher.

This lever carries a roller 38 which bears on the circumference of the cam 20 and is held against the cam by a spring 39. This cam is suitably formed to cause the pusher 32 to move back and forth rapidly through the range above described with each revolution of shaft 12 and to remain stationary through a large fraction of the cycle when in its position of nearest approach to the rolls. Thus on each revolution of the cam shaft, the pusher is quickly withdrawn from the position in which it is shown in Figs. 1 and 4, far enough to permit descent of the pile of envelopes in the magazine 34 with placement of the lowest one of the pile in line with the pusher; and is immediately thereafter quickly advanced to bring the lowermost envelope to the nip of the rolls, which are stationary at that time. Preferably the edge of the pusher which bears on the envelope is provided with a lip 40 shown in Fig. 4, which overlies the adjacent edge of the envelope while propelling it, and after the advancing edge has entered the open space between the rolls 27 and 28 and been arrested by the contacting portions of the rolls. When so arrested, the advancing edge of the envelope is overlapped by the roll 28.

A suction cup 41 is mounted stationary in the table 10 between the magazine and the axial plane of the rolls and located where it is overlaid by the receiving end portion of the envelope *a'* which is in receiving position, (Figs. 4, 7 and 8). This cup is coupled by a pipe line 42 with a vacuum chamber 43 from which a pipe 44 leads to air exhausting means, not shown, which may be of any suitable character. A second suction cup 45 is located above the cup 41 in substantial

alignment therewith and is mounted on the lower end of a tube 46 which is held by a carrier 47 and is coupled by a pipe 48 with the vacuum chamber 43. Carrier 47 in turn is mounted on a bar 49, which is reciprocable through table 10 and through guides 50 and 51 which extend above and below the table (Fig. 5). The bar 49 is coupled at its lower end by a pin and slot connection with a lever 52 pivoted to a bracket 53 (suspended from the table or otherwise supported by the machine frame). This lever carries a cam follower roll 54 which is held by gravity against the circumference of the before mentioned cam 18, which is here called for convenience the suction cam.

A vent valve 55 is connected at a convenient point in the pipe line 48 and is equipped with an operating arm 56 arranged to be engaged and moved by a stud 57 on the carrier 47 when the latter is brought to the extreme upper limit of its rising movement from a point near said upper limit. The movement then given to the valve arm 56 opens the valve and allows inflow of air to the vacuum system, whereby the vacuum is broken in the pipe 46 and cup 45. Arm 56 is arranged to close the vent valve and cause it to remain closed at all times except when the carrier is at and near the upper limit of its movement. A constant vacuum is maintained in the suction box 43.

The function of the cups 41 and 45 is to spread apart the sides of the envelope which has been brought to the position *a'* indicated in Fig. 4. Cam 18 therefore is formed with a low dwell *b*, a rise *c*, a high dwell *d*, a short rise *e*, a second high dwell *f*, and a descent *g*. These portions of the cam are angularly so related to the pusher 20 that the cup 45 is held elevated by the dwell *f* while a filled package is removed and pusher 32 then advanced to bring an envelope to the position *a'*; the descending surface *g* then allows the cup 45 to descend and bear on the upper side of the envelope, the rise *c* then lifts the cup 45 and draws with it the upper side of the envelope away from the under side thereof, which is then held down by the stationary cup 41. Dwell *d* occupies so much of the cycle as is required for advancing cleaners into the envelope by means later described. So long as the parts *g*, *b*, *c* and *d* support the follower roll 54, the vent or bleeder valve 55 is closed and suction is exerted by cup 45 on the envelope. The final rise *e* lifts the carrier 47 by an additional amount which is sufficient to open the valve 55, whereby the vacuum in the cup 45 is broken and the envelope is released therefrom. From this point on the cycle is repeated.

Although the pusher 32, in continuing its movement for a short distance after the envelope is arrested by the rolls 27, 28, causes the sides of the envelopes to be somewhat bowed, it does not necessarily bend all of them so that the sides are spread apart. Depending on whether the sides of an envelope are perfectly flat, or more or less warped, the sides may be sprung apart, or both sides may be sprung either downward or upward. But the suction cups, operated in the manner described, insure that the under side of the envelope will be held down and the upper side raised so as to open the receiving end widely enough to admit a bunch of the cleaners.

But the suction elements can be depended on alone to open the mouth of the envelope and the pusher may be stopped as soon as the advancing envelope engages the rolls. However, it is pre-

ferred that both agencies act in conjunction in the manner described, in order to give complete assurance of opening the receiving mouths of all the envelopes widely enough.

The pipe cleaner stock is provided in strips or strings of indeterminate length, which may be many feet or yards. A number of such strips or strings (as one dozen, more or less, the number prescribed as the contents of a given package), are wound in parallel, and more or less bunched fashion, on a spool or reel, not here shown, which is mounted in convenient proximity to the packaging machine and from which the strip stock is led to the machine. Figs. 7, 8 and 9 show at *h* a bunch of cleaner strip material passing between a guide 58, a feeder 59 and a throat 60. The guide and throat are mounted stationary on the machine frame with the throat 60 near the receiving end of the envelope which is in loading position, and the guide 58 at a distance therefrom somewhat greater than the prescribed length of the finished cleaners. That is, the space between these members is long enough to permit travel of the feeder 59 in this space, back and forth, through a distance equal to the prescribed length of the cleaners. The feeder is provided with a fixed gripper 61 at one side of the bunch of stock and a pivoted gripper 62 at the other side of the bunch, the latter gripper being pressed by a spring 63 toward the bunch. These grippers are preferably made as thin metal plates having serrations on their free edges and inclined convergently toward the throat 60. Similar grippers 64 and 65, the latter being pressed upon by a spring 66, are mounted on the fixed guide 58 to prevent the bunch of stock from being pushed back when the feeder withdraws between successive feeding strokes.

The throat 60 has a tapered passageway of which the smaller end is next to the receiving envelope and aligned therewith, having a height and width less than those of the open mouth of the envelope. A knife 67 is guided to reciprocate close against the surface of the throat member 60 and across the delivering orifice thereof so as to cut off the cleaners after they have been advanced into the envelope.

The feeder 59 thus described is mounted on a slide or carrier 68, which is mounted to reciprocate on a guide 69 secured to the front side of the table 10 in parallel with the alignment of guide 58, throat 60 and receiving envelope. This slide is connected by a link 70 with a lever 71 which is pivoted at 72 (Fig. 2) to a bracket 73 on the machine frame and carries a follower roll 74 engaging the operating end face of cam 17. A spring 75, connected to lever 71 and an anchorage on the frame, holds the follower 74 against the cam. The axially offset operating face of cam 17 is angularly related to the cams 20 and 18 so as to cause retraction of the feeder while the envelope is being placed in receiving position and opened, and advance of the feeder while the envelope is stationary with its receiving mouth widely opened.

The cut off knife 67 is connected by a pin and slot connection with a lever 76, which is pivoted to the bracket 53 beside lever 52 and carries a follower roll 77 bearing on the circumference of cam 19. Gravity, supplemented by a spring 78, holds this follower against cam 19. This cam has a projection *k* of short angular extent, so related to the cams previously described as to cause advance and retraction of the knife when the feeder reaches the end of its feeding stroke and before the loaded package is removed. It is other-

wise formed to retain the knife in its retracted position during all the rest of the cycle.

It may be remarked at this point that, although the lever 52 has been described previously as held against its operating cam 18 by its own weight and that of the parts which it operates, I may apply to it a spring, such as the spring 78 to impart a more rapid downward movement to these elements than is caused by gravity alone, if desired.

The rolls 27 and 28 are intermittently rotated to remove filled envelopes from receiving position. For rotating them, a ratchet 79 (Fig. 3) is mounted on shaft 13 adjacent to roll 27 and a pawl 80 is mounted on a pawl carrier 81 and is spring pressed to engage the ratchet. Pawl carrier 81 is mounted to rotate about shaft 13 and is connected by a link 82 with a lever 83 pivoted at 84 on a fixed bracket 85. A forked link 86 is connected by a pivot 87 to lever 83 and has two parallel arms which embrace the cam shaft 12. The link 86 carries a follower roll 88 which is held in contact with the circumference of cam 21 by a spring 89 connected with lever 83 and with a fixed anchorage on the frame. The major part of cam 21 is concentric with shaft 12 and it has a rapidly descending surface 90 and rapidly rising surface 91 which merge with one another close to the hub of the cam. When the descending surface 90 passes the follower roll, the pawl is caused to slip idly over the ratchet, and the rising surface causes the pawl to rotate the ratchet and the feed rolls (roll 28 being rotated by the gear pair 29-30) sufficiently far to propel the filled package between and clear of the rolls. The cam surface 91 is suitably located to effect this propelling action after the pipe cleaner strips have been placed in the envelope and cut off, and before the pusher 32 has brought another envelope into the charging location.

A conveyer belt 92 is supported by rolls 93 and 94 (Fig. 1) with its upper stretch extending horizontally and in position to receive packages delivered by the feed rolls. It is advanced step by step in time with the feed rolls by a pawl 95 acting on a ratchet 96 connected with the roll 93. The carrier 97 of pawl 95 is pivoted to one end of a link 98, the opposite end of which is coupled by a pin and slot connection 99 with lever 83, at a point nearer to the fulcrum thereof than the point at which link 82 is connected. Thus the lever 83 advances the conveyer belt at the same time that it propels the feed rolls, but through a shorter distance. Thus the filled packages are deposited on the conveyer with overlaps. They are eventually discharged from the conveyer into a receptacle of any kind desired.

It will be apparent from the foregoing that the machine is entirely automatic in respect to placing containers in receiving position, loading the containers with the material to be packaged, cutting off the material in pieces of prescribed length, and delivering the filled packages to a final receiver. The only service required of an attendant is to replenish the supply of envelopes in the magazine 34 from time to time and substitute new quantities of the material to be placed in the envelopes.

Evidently goods other than the specific pipe cleaners herein described can be packed in envelopes or other analogous holders by the machine here illustrated and other machines containing the same principles but of possibly different designs.

It is within my contemplation to provide adjustments and/or substitute parts by which one machine can be adapted for packaging pieces of various lengths, singly or in any desired numbers, in containers of various dimensions and types, all within the scope of the protection afforded by the appended claims.

What I claim and desire to secure by Letters Patent is:

1. A machine for packing elongated articles comprising a supporting structure, a magazine thereon adapted to hold a stack of open-ended flat containers having flexible sides and resting on the supporting structure, a pusher movable on the supporting structure from one side of the magazine to the other side across the bottom thereof in a path transverse to the length of the containers for removing the bottom container therein and placing such container in a receiving position, suction cups disposed above and below such position, means for moving one of such cups toward and away from the other to engage the sides of the container and draw them apart so as to open the mouth thereof, a feeder mounted on the supporting structure to reciprocate in a path aligned with said receiving position and the length dimension of the container toward and away from the mouth of a container in such position, and means for reciprocating said feeder in timed relation with the actions of said pusher and container-opening means so that the feeder is advanced when a container is in the receiving position with its mouth open.

2. A machine for packing elongated articles comprising a supporting structure, a magazine thereon adapted to hold a stack of open-ended flat containers having flexible sides, a pusher movable on the supporting structure from one side of the magazine to the other side across the bottom thereof for removing the bottom container therein and placing such container in a receiving position beside the magazine, normally stationary feed rolls located at the far side of such receiving position from the magazine and so arranged that the advancing boundary of the displaced container is brought to the nip of the rolls by the pusher, a feeder movable in a path parallel with the axes of said rolls and aligned with said receiving position toward and away from the location occupied by the mouth of a container when in receiving position for placing in such container the material to be packed therein, and actuating means for respectively reciprocating the pusher, reciprocating the feeder, and intermittently rotating said rolls in the above named sequence.

3. A packaging machine of the character described, comprising a supporting structure, a magazine on said structure adapted to hold a stack of open mouthed substantially flat containers having flexible walls, a pusher guided to move across the bottom of said magazine from a displaced position at one side thereof in a path which is transverse to the length dimension and side edges of the containers in the magazine, a pair of normally stationary delivery rolls arranged at the far side of the magazine from the pusher with their nipping portions in substantial alignment with the path of the pusher, means for reciprocating the pusher in the before named path, whereby it is caused to displace a container from the magazine and bring such container into the space between the magazine and rolls with its advanced side edge

at the nip of the rolls, a feeder movable in a path transverse to that of the pusher and located in substantial alignment with the space occupied by a container when displaced from the magazine by the pusher, and with the length of such container, means for reciprocating the feeder between a point near the mouth of such a displaced container and a second position farther removed from such mouth, whereby to bring material into the container, and means for intermittently rotating said rolls in a direction to cause them to remove filled containers from their receiving position.

4. The packaging machine set forth in claim 3, combined with a trimmer located adjacent to the mouth of a container in receiving position, and means for operating said trimmer to cut off the material placed in such container by the feeder.

5. A packaging machine comprising a supporting structure, a magazine on said structure rising from the table adapted to hold a stack of flexible-walled open-ended envelopes resting on the table, a pusher mounted to reciprocate on the supporting structure beneath the magazine from a withdrawn position at one side of the magazine to the other side thereof in a path which enables it to remove an envelope from the stack in the magazine, suction cups arranged above and below the location to which envelopes are brought by said pusher in its propelling movements in positions enabling them to engage and apply suction to the outer surfaces of opposite sides of the envelope, means for withdrawing one of said cups from the other so as to spring the sides of the envelope apart and open the mouth thereof, guides arranged to hold elongated slender articles in alignment with the envelope displaced by said pusher, a feeder for such articles located between said guides, and means for reciprocating said feeder in alignment with the guides.

6. A packaging machine comprising a support adapted to hold an open-ended container in a receiving position, guides disposed to hold strip material of indeterminate length in alignment with the mouth of such a container, a feeder movable back and forth between said guides in alignment with them and having means arranged to grasp the material when the feeder is moving toward that guide which is nearest to the container, and a trimmer between the container and nearer guide for cutting off the material which has been placed in the container.
